UNITED STATES PATENT OFFICE.

THEODORE S. ARCHIBALD, OF MELROSE, MASSACHUSETTS.

MACHINE FOR CONDITIONING SASH BARS.

Application filed November 16, 1925. Serial No. 69,554.

This invention relates to a mechanism more particularly intended for removing old putty and points from sash-bars such as are used in the construction of greenhouses.

5 When greenhouses are dismantled and the glass is removed from the sash-bars, before the latter can be used again the old putty and the glass-retaining elements or points must be thoroughly removed. As the old 10 putty in most cases is very hard and clings to the bars, removing by hand is tedious and time-consuming. The use of mechanical cutters has heretofore been found impracticable, as the putty contains abrasive 15 ingredients which quickly dull the cutting edge of the instrument and destroy its practical utility.

According to my invention the putty is first subjected to crushing pressure so that 20 it is crumbled and it is then dislodged or dug out, the glass-retaining points being either removed or cut off. While old putty is hard and offers great resistance to a cutting edge, it crumbles under properly applied pressure, 25 and the fragments are quickly and easily removed with but slight wear on the machine.

An advantageous feature of the machine is the use of ordinary milling cutters. 30 These, being standard parts, are relatively cheap and easily obtainable. They are also easily resharpened when necessary.

A preferred embodiment of my invention is disclosed in the drawings and hereinafter 35 described as follows:

Figure 1 is a plan of the complete mechanism.

Figure 2 is a side view of the same.

Figure 3 is a sectional view taken on the 40 line III—III in Figure 1.

Figure 4 is an enlarged detail showing the action of the crushing and cleaning wheels on the putty and sash-bar.

Figure 5 is a fragmentary perspective 45 view of a conventional sash-bar before being cleaned, this type of bar being provided with two grooves.

Figures 6 and 7 are fragments of other customary forms of sash-bars.

50 Figure 8 is a view of a modified form of crushing wheel and supporting roll adapted for use with the kind of sash-bar shown in Figure 7.

55 On a raised platform 1 is mounted a frame 2, in which are journaled rolls 3 for supporting a sash-bar 4 as it passes through the

machine, the sash-bar there shown being provided with two grooves or rabbets. The frame 2 is provided with lugs 5 through which are threaded screws 6 which permit 60 adjustment of the height and level of the frame 2. Operating on the upper part of the sash-bar are wheels 7. One or more of these wheels may be used for each groove acted upon. Herein are shown two such 65 wheels acting in each groove. In order to act simultaneously on both grooves of the sash-bar, the wheels are mounted in pairs on shafts 9, spacing members 8^a being employed to space the wheels of each pair from 70 each other. The wheels 7 may be keyed to the shafts 9, but in practice it is found sufficient to clamp them tightly between sleeves 8 which may be made integral with the shafts 9 or, as shown, pinned thereto, 75 and nuts 9^a. Loosely mounted on the spacing members 8^a are collars 8^b. These collars may be made of such a diameter that when the machine is operating on a strip of sash-bar, such as shown in Figure 5, the peripheries of the collars 8^b will ride on the ridge 80 of the sash-bar when the teeth of the wheels 7 can just touch the bottoms of the grooves on either side of the ridge. This protects the bottoms of the grooves of the sash-bar, 85 since the collars 8^b bear on the ridge of the sash-bar and act as stops to limit the downward movement of the wheels 7 and thus prevent the teeth of the wheels 7 from indenting or injuring the sash-bar. Collars 90 of different length and diameter may be interchanged according to the width and height of the ridges on the sash-bars which are to be cleaned. The pressure of the two pairs of wheels on the material acted upon 95 is equalized by employing the shafts 9 as end members of a rockable frame 10, having side members 11. These side members are provided with enlarged ends 12, in which the ends of the members 9 are journaled. In 100 the machine shown on the drawings, the end pieces 9 rotate with the sleeves 8 and the wheels 7. If preferred, however, the end pieces 9 may be fixed in the ends of the side members 11, the sleeves 8 and wheels 7 being assembled in such a way as to rotate on the end member 9. The side members 11 are also provided with enlarged portions 13 at their mid-points, which portions respectively contain bearings for a rotatable shaft 14 and stud shaft 15, on which shafts the frame 10 is free to rock.

The shafts 14 and 15 are respectively journaled in enlarged portions 16 and 17 of side bars 18, 19 of the U-shaped frame 20 positioned outside of the frame 10. This U-shaped frame has an end bar 21 at one end and enlarged portions 22 at the other end, said portions having bearings for the main drive shaft 23. The frame 10 is thus rockably supported by the U-shaped frame 20, which in turn can be swung about the shaft 23.

The wheels 7 are operatively connected with driving shaft 23 in any preferred manner. Herein are shown gears 24 mounted on shafts 9, which mesh with a gear 25 mounted on a shaft 14. Shaft 14 also carries gear 26 which meshes with an idle gear 27 mounted on side bar 18. Gear 27 meshes with gear 28 fixed on drive shaft 23.

20 A pair of wheels 29, preferably similar to wheels 7, are mounted on shaft 23 to rotate therewith. It will be seen from the arrangement of the gearing that wheels 7 and wheels 29 rotate in opposite directions, as indicated by the arrows.

Wheels 7 and 29 are preferably provided with teeth having cutting edges, which teeth may also be undercut. Ordinary milling cutters have been found to be admirably suited for the purposes of the device. The arrangement of the teeth of wheels 7 and 29 is preferably as shown in Figure 4. A preferred form of milling cutter suitable for use in this machine is also provided with 30 cutting edges on the sides of the teeth as well as on their ends. Wheels 7 are rotated in a direction to present the backs of the teeth to the putty on the sash-bar for the purpose of crushing the same, while wheels 35 29 are rotated in the opposite direction to present the cutting edges to the crushed putty and to dig under and remove the crumbled fragments. The crushing of the putty by the wheels 7 reduces to a minimum 40 the wear on the teeth of wheels 29.

In order to bring the wheels 7 into operative relation with the material acted on, the frame 20 is swung down with the assembly of members supported by it by depressing the treadle 30 pivotally supported on the standard 31 and connected to the frame 20 by a rod 32 which may be attached to any part of the frame. Herein it is shown attached to an extension 33 of the end member 55 21.

A latch 34 is pivotally mounted on standard 35 and engages side-bar 19 to retain frame 20 in its lowered position, that is, the position in which wheels 7 exert their maximum crushing effect.

There is ordinarily sufficient pinching effect between wheels 7 and supporting rolls 3 to feed the bars through the machine. Additional feeding means, however, are 60 preferably employed, comprising a pair of 65

vertical rolls 36 suitably spaced to receive a sash-bar, and a similar pair of rolls 37 positioned at the opposite end of the machine, the two pairs of feed rolls being aligned to direct the sash-bar beneath the crushing wheels 7 and the cleaning wheels 29. The feed wheels 36 and 37 engage the sides of the sash-bars, and have the further function of removing any longitudinal twist that may be in the sash-bar from the portion 75 passing through the machine.

The feed wheels 36 and 37 are positively driven from shaft 23 by any preferred connection. Herein are shown gears 38 fixed to the vertical shafts 39 on which feed rolls 36 are also fixed. The gears 38 mesh with each other and are driven by a gear 390 mounted on shaft 40, which is driven by shaft 41 through bevel gears 42 and 43. The shaft 41 is connected by bevel gears 44 and 45 to shaft 46. On shaft 46 is a gear 47, which drives meshed gears 48. These gears, together with the rollers 37, are respectively mounted on vertical shafts 49. The gears and shafting connecting the feed rollers are preferably mounted below the raised platform 1, as shown. On shaft 46 is fixed a sprocket 50, which is connected to a sprocket 51 by chain 52. The sprocket 51 is mounted on the drive shaft 23, which is coupled at 521 to a reduction gear 53. A motor of any suitable kind, indicated at 54, is connected by the coupling 55 to the reduction gear 53.

In operating the machine, the end of the 100 sash-bar is introduced beneath the wheels 7. As the end of the bar passes under the second pair of wheels 7, frame 20 is depressed by bearing down on treadle 30 and retained in its depressed position by latch 34. The machine is so arranged that the peripheral speed of wheel 7 is approximately equal to the speed of travel of the sash-bar through the machine. As the sash-bar passes through, the backs of the teeth of wheels 7 105 exert crushing pressure on the putty progressively at spaced points along the bar, and the gearing connecting the first and second pairs of wheels 7 is preferably arranged so that the points of contact of the teeth of the second pair of wheels will be substantially midway between the points of contact of the teeth of the first pair of wheels. This insures a thorough crumpling or disintegration of the putty before it passes to the cleaning wheels 29. The latter, rotating in such a direction as to present the cutting edges of their teeth to the crushed putty, readily dig under and scoop out the crumbled fragments, leaving the grooves 110 120 clean.

The form of machine shown in the drawings is adapted for use with a sash-bar having two grooves. By slight modification of the form and position of wheels 7 and 29 125 130

and supporting rolls 3, other bars or strips with different cross-sections, such, for example, as are shown in Figures 6 and 7, can be cleaned.

5. While my invention is particularly intended for cleaning the glass-retaining materials from sash-bars, it is capable of other applications wherever a similar problem is encountered.

10. I claim:

1. In a machine for cleaning material from grooves of wooden sash-bars and the like, comprising means for progressively disintegrating the material, and additional 15 means for dislodging the disintegrated material from the grooves.

2. A machine for removing friable material from grooves, comprising positively rotated means for crushing the material and 20 additional means for dislodging the crushed material from the grooves.

3. A machine for removing putty from grooved sash-bars, comprising means for applying crushing pressure to the putty at spaced points lengthwise of the grooves to break it into fragments, and additional 25 means for dislodging the fragments of putty from the sash-bars.

4. In a machine for removing glass-sealing materials from grooved sash-bars, means for applying crushing pressure to the materials, means for cleaning the crushed materials from the grooves, means for feeding the sash-bars past the crushing 30 and cleaning means, a source of power, and means operatively connecting all said means to the source of power.

5. In a machine for removing putty from sash-bars, a platform, a motor, a pair of standards mounted on the platform, a drive-shaft journaled in the standards, a reduction gear operatively connecting the drive shaft with the motor, an outer frame comprising side bars and an end bar, the side 40 bars having in their ends remote from the end bar bearings to receive the drive shaft whereby the frame is swingable about the drive shaft, a pair of bearings at opposed intermediate points of the side-bars, a stud-shaft secured in one bearing, a rotatable shaft journaled in the other bearing, an inner frame rockably supported on the stud-shaft and rotatable shaft and having end pieces on opposite sides of the rocking axis, a pair of spaced wheels carried on each end 45 piece, means including the rotatable shaft operatively connecting the wheels with the drive shaft, a pair of spaced wheels mounted on the drive shaft and aligned respectively with corresponding wheels on the end pieces, operator actuated means for swinging the frames so as to press the frame-supported 50 wheels against the putty on the sash-bars, a pair of feed rolls mounted at each end of the platform, means operatively connecting

the feed rolls with the drive shaft, and means for supporting the sash-bars intermediate the pairs of feed rolls.

6. In a machine of the class described, a toothed wheel, means for rotating the wheel, 70 means for supporting said wheel in a manner to permit said wheel to be pressed against the putty in a pane-receiving groove of a sash-bar to crumble the putty, and means for dislodging the crumbled putty 75 from the groove.

7. In a machine of the class described, a milling cutter having undercut teeth, means for pressing the cutter against the putty in a groove of a sash-bar, means for rotating 80 the cutter in a manner to present the backs of the teeth to the putty to crumble the putty, a second milling cutter, and means to rotate the second cutter in a manner to present the cutting edges of the teeth to the 85 crumbled putty.

8. In a machine of the class described, means for crushing and dislodging putty from a sash-bar, and means for supporting the sash-bars in a position to be operated 90 on by the crushing and dislodging means.

9. In a machine of the class described, means for applying crushing pressure to the putty in a groove of a sash-bar, means for supporting the sash-bar against the pressure 95 of the crushing means, and means for cleaning the crushed putty from the groove.

10. In a machine of the class described, a plurality of wheels each having cutting teeth, means for rotatably supporting said 100 wheels in operative relation to the pane-securing material in a groove of a sash-bar to act successively on said material, means for rotating the first-acting wheel in a direction to bring the back faces of its teeth 105 against said material to crush and disintegrate the same and for rotating a successively acting wheel in a direction to cause its cutting teeth to dig under said crushed material and remove it from said groove. 110

11. In a machine of the class described, a drive shaft, a frame swingably mounted thereon, a plurality of toothed wheels supported by the frame, a toothed wheel mounted on the drive shaft, the toothed 115 wheels being positioned in a common plane, means operatively connecting the frame-supported wheels with the drive shaft, and means for supporting a sash-bar in a position to be operated on by the wheels. 120

12. In a machine of the class described, a plurality of means for successively crushing the putty on a sash-bar, and means for pressing the crushing means against the putty including means for equalizing the 125 pressure of the several crushing means.

13. In a machine of the class described, a plurality of means for successively crushing the putty on a sash-bar, means for pressing the crushing means against the putty in- 130

cluding means for equalizing the pressure of the crushing means, and means for cleaning the crushed putty from the bar.

14. In a machine of the class described, a frame swingably mounted at one end, a plurality of toothed wheels supported by the frame for successive crushing engagement with the putty on a sash-bar, means for swinging said frame to press the wheels against the putty, and means for equalizing the pressure of successive wheels thereagainst.

15. In a machine of the class described, a frame swingably mounted at one end, a plurality of toothed wheels supported by the frame for successive crushing engagement with the putty on a sash-bar, means for swinging the frame to press the wheels against the putty, means for equalizing the pressure of successive wheels against the putty, and means for cleaning the crushed putty from the bar.

16. In a machine of the class described, means for crushing and dislodging the putty on sash-bars, said means comprising toothed wheels positioned in the same plane and rotated in opposite directions.

17. In a machine of the class described, means for crushing and dislodging the putty on sash-bars, said means comprising three pairs of toothed wheels positioned in parallel planes for simultaneous operation on both sides of a sash-bar, and means for rotating the first two pairs of wheels in one direction and for rotating the third pair in the opposite direction.

18. In a machine of the class described, tools having undercut teeth, means for presenting the backs of the teeth to putty on a sash-bar in a manner to crush the putty, other tools having undercut teeth with cutting edges, means for presenting the cutting edges of the teeth to dig under the crushed putty, and means for feeding the sash-bar past the tools.

19. In a machine of the class described, a plurality of wheels having undercut teeth with cutting edges, means for supporting the wheels in successive aligned pairs in position

for simultaneous successive operation on the putty in opposed rabbets of a sash-bar, means for rotating the first pair of wheels in a direction to present the backs of the teeth to the putty to crush the same, means for rotating the last pair of wheels in a direction to present the cutting edges of the teeth to dig out the crushed fragments of putty, and rollers spaced from the wheels to permit the sash-bar to be passed therebetween.

20. In a machine of the class described, rotatable means for crushing the putty on a sash-bar, means for dislodging the crushed putty from the bar, means for feeding the sash-bar past the crushing and dislodging means, means for rotating the crushing means with a peripheral speed substantially equal to the speed of travel of the sash-bar and in a direction with the motion of the sash-bar, and means for rotating the dislodging means in a direction opposed to the motion of the sash-bar.

21. In a machine of the class described, means for crushing putty in a groove of a sash-bar, means for moving the crushing means into position for crushing engagement with the putty, and means for retaining the crushing means in such position.

22. In a machine of the class described, a swingable frame, means supported by the frame for crushing putty in a rabbet of a sash-bar, means attached to the frame for moving the crushing means into crushing engagement with the putty, a latch engaging the frame to retain the crushing means in crushing engagement with the putty, and means to clean the crushed putty from the rabbet.

23. The method of cleaning putty from sash-bars, which comprises rotating a milling cutter in a direction to bring the backs of the cutter teeth into crushing engagement with the putty and rotating another milling cutter in the opposite direction to cause the cutting edges of the teeth to dig under the crushed fragments of putty.

In testimony whereof I have affixed my signature.

THEODORE S. ARCHIBALD.
